UNITED STATES PATENT OFFICE.

RUDOLPH BUSCH, SR., OF SHELLTOWN, MARYLAND.

PAINTER'S DUSTER SAFETY CLIP.

Application filed May 15, 1928. Serial No. 277,987.

The object of my invention is to provide a novel clip to be worn by painters for the purpose of conveniently carrying an extra brush for use in dusting surfaces to be painted and to provide novel means for adjusting such a device for holding brushes of different sizes.

I attain these and other objects of my invention by the device illustrated in the accompanying drawings, in which,—

10 Figure 1 is a front elevation of the invention in use;

Fig. 2 is a side elevation of same;

Fig. 3 is a longitudinal section through the device with the brush removed; and

15 Fig. 4 is a rear plan view of the device with the brush removed.

Like numerals designate like parts in each of the several views.

Referring to the accompanying drawings, 20 I provide a U-shaped clip having a back 1, front 2, and resilient U-shaped connecting portions 3, the said U-shaped portions being cut away as shown in Figs. 1 and 3 to permit the handle of the paint brush to extend therethrough. The back of the clip has apertures 10 through same by means of which it may be fastened to any desired portion of the garment 11, such as the rear pocket as shown. Both the back and front of the clip 25 are provided with curved ends 4. Integral with the back of the clip are tongues 5 which extend at right angles to member 1 and which have spaced apertures 6 to receive trunnions 9 of a clip lever 8, which clip lever has an L-shaped end 7 bearing against the outer surface of the front 2 of the clip as shown in Fig. 2.

In use the clip lever 8 is swung to the open position shown in Fig. 3 and the handle 12 of the brush is inserted as shown in Fig. 2 through the opening in the U-shaped portions of the clip as shown in Fig. 1. By swinging the clip lever from open position, as shown in Fig. 3, to closed position, as shown in Fig. 2, the front of the clip is caused to press against the handle 12 and thus hold it in place. The apertures 10 in the back of the clip permit of its being readily fastened to the garment of the wearer at a convenient portion thereof, such as the rear pocket.

What I claim is—

1. A clip for holding a duster brush used by painters, consisting of a U-shaped clip having opposite arms extending at right angles to the back of the clip, an L-shaped clip lever pivotally mounted in said arms and having its L-shaped end bearing against the front of the clip, the front and back of the clip being connected by a U-shaped resilient portion, the free ends of the front and back of the clip being curved to snugly engage the handle of the paint brush.

2. A clip for holding a duster brush used by painters, consisting of a U-shaped clip having opposite arms extending at right angles to the back of the clip, an L-shaped lever bearing against the front of the clip, the front and back of the clip being connected by a U-shaped resilient portion, said U-shaped portions being cut away to permit the handle of the paint brush to extend therethrough.
